(57) **CLAIM**

The ornamental design for a wallet, as shown and described.

DESCRIPTION

FIG. 1 is a front, first side, and bottom perspective view of a wallet embodying the new design;

FIG. 2 is a back, second side, and bottom perspective view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is a first side and bottom perspective view showing an interior portion of the wallet in an open position;

FIG. 10 is a second side and bottom perspective view showing an exterior portion thereof;

FIG. 11 shows an exterior portion of the wallet in the open position;

FIG. 12 shows an interior portion thereof;

FIG. 13 is a first side view thereof;

FIG. 14 is a second side view thereof;

FIG. 15 is a side and front perspective view of a pen detached from the wallet; and,

FIG. 16 is a side and back perspective view of the pen thereof.

The evenly dashed broken lines on claimed surfaces depict stitching and form no part of the claim. The evenly dashed broken lines adjacent structure shown with no surface shading depict portions of the wallet in which the claimed design is embodied and form no part of the claim.

1 Claim, 16 Drawing Sheets
